FIG. 1.

FIG. 2.

FIG. 3.

FIG. 4.

Edward E. Ziegler.
INVENTOR

BY Victor J. Evans

ATTORNEY

Alfred G. Brattin
WITNESS.

UNITED STATES PATENT OFFICE.

EDWARD E. ZIEGLER, OF PHILADELPHIA, PENNSYLVANIA.

HAND VIBRATOR.

Application filed July 19, 1921. Serial No. 485,906.

To all whom it may concern:

Be it known that I, EDWARD E. ZIEGLER, a citizen of the United States, residing at Philadelphia, in the county of Philadelphia and State of Pennsylvania, have invented 5 new and useful Improvements in Hand Vibrators, of which the following is a specification.

This invention relates to massage apparatus and analogous devices for communicating vibratory treatments to various parts of the human body and it has more particular reference to that type or form of apparatus commonly designated hand-vibrators that are employed by hairdressers for 10 massaging the human face, such apparatus however being equally serviceable for treating the limbs or body of a patient locally for certain ailments or muscular afflictions 15 and where it is desirable to stimulate the blood circulation.

The primary object of my invention is to provide a hand-vibrator of the kind referred to in which the vibrations are effectively directed to the finger-tips instead of being partly distributed over the hand and arm of the user as has hitherto been prevalent with devices of the nature referred to.

Another object of my invention is to provide a hand-vibrator having insulating cushions removably mounted thereunder whereby cleanliness is more effectively ensured whilst the device is resiliently supported in its entirety on the back of the 35 operator's hand.

A further object of this invention is the provision of a hand-vibrator characterized by a novel construction of vibrator-shaft and weight which ensures an effective end 40 or axially directed vibratory thrust.

A still further object of my invention is to provide a hand-vibrator which is simple in construction, cheap to manufacture, light in weight and by virtue of its pattern is 45 much more comfortable and effective in use, as well as thoroughly sanitary in every respect.

With the foregoing and other objects in view as will become more apparent as this 50 description proceeds, my invention consists essentially in the novel features of construction, combinations and arrangements of parts hereinafter more fully described and specifically defined by the appended claims.

55 In the further disclosure of the invention reference is to be had to the accompanying

sheet of explanatory drawings constituting a part of this specification and in which like characters of reference designate the same or corresponding parts in all the views. 60

Figure 1 is a side elevation of my improved vibrator as attached on the operator's right-hand ready for use.

Figure 2 is a longitudinal sectional elevation of the hand-vibrator removed from 65 the operator's hand.

Figure 3 is a perspective view of the rotary weighted shaft; and,

Figure 4 is an enlarged plan view of the removable insulating cushioning means hereinafter more particularly referred to. 70

Referring more particularly to the views my improved hand-vibrator comprises a main or cylindric body portion 10 which is provided on its underside with an integral 75 depending longitudinal tongue or rib 11 of appropriate cross-section to seat snugly in a correspondingly shaped groove or channel 12 provided for the purpose longitudinal of a standard or block 13 having a hollowed 80 out base 14 including front and rear rest sections 15, 16 respectively, said main or cylindric body portion 10 being securely held in place on the block 13 by countersink screws 17 as will be clearly understood on 85 an examination of the drawings. It is to be here remarked that the above mentioned manner of connecting the parts 10 and 13 effectively prevents any lateral displacement or movement of the former relative to the 90 latter. Adapted for clamping attachment within the aforesaid base 14 is a fiber sheet 18 stiffened or braced by a metal strip 19 and said fiber sheet 18 has secured thereto as by lines of stitching 20 spaced rectangular blocks 21, 22 of appropriate insulating 95 material such as soft rubber, the latter 22 being disposed under the rest section 15 and seating in use on the back of the operator's hand 23 immediately in the rear of 100 the knuckle joints; a composite rubber and leather strap 24 provided with eyelets or spaced grommets 25 engageable on a stud 26 retaining the device securely in place. The former block 21 is disposed beneath the 105 forward and downward inclined rest section 15 and seats upon the two middle fingers of the user's hand between the knuckle and first finger joints an elastic or rubber band 27 holding said block snugly on the aforementioned fingers, and it will be readily seen that by this arrangement of parts the first

and little fingers are left perfectly free, whilst the forward parts of the second and third fingers are similarly free below the first finger joints; also that the vibrator in its entirety is supported in spaced relation to the hand over the knuckle joints thereof. The aforesaid fiber sheet 18 and metal strip 19 are clamped within the base 14 by a screw 28 as will be clearly seen by Figure 2 of the drawings, whilst I may attach the rubber blocks to the fiber sheet in any other appropriate manner that lends itself to easy attachment and disconnection for purposes of cleaning or renewal.

15 Freely rotatable within the aforesaid cylindric body portion 10 is a rotatable weight 29 integral with a shaft 30 journaled in the bearing 31 at the forward end of said cylindric body 10, said shaft 30 being adapted to be driven from the flexible shaft of an electric motor—not shown—in any of the well known ways and as will be self-evident to those acquainted with the art to which my invention appertains. The rotatable weight 29 is preferably made as illustrated most clearly by Figure 3, that is to say, it is formed with a disc portion 32, a semi-segmental disc portion 33, and intervening stepped portions 34, 35, the form of which is segmental in cross-section whereas the latter is of relatively larger and crescent-shaped cross-section thus making the forward end of said weight 29 comparatively heavier than the rear portion and thereby ensuring what may be termed a forwardly directed eccentric thrust which will ensure a constant non-variable vibration of the device when in use. A stub or extension 36 of the shaft 30 is journaled in a bearing 37 integral with the removable cap 38 screw threaded into the end of the cylindric body portion 10.

By the use of the compound stepped weight 29 it will be readily seen that an even and forwardly directed vibration is obtained and by virtue of the peculiar shape a considerable number of vibrations per minute are ensured, said vibrations being mainly directed to the two middle fingers 50 of the operator's hand and thereby rendering the device better adapted for local treatments.

In using my improved hand-vibrator the device is strapped on the hand by first passing the two inner or middle fingers into the elastic band or loop 27 until the latter is positioned as shown in Figure 1, whereupon the composite strap 24 is adjusted into position and hooked on to the stud 26, the motor is then started whereupon it will be easily seen and understood that the palm of the hand, first and little fingers will be

free to grasp or press upon the part of the body to be treated whilst the inner fingers will transmit the vibrations directly thereto. Furthermore, it will be observed that by the use of the soft rubber rest blocks or cushions 21, 22, no impediment is placed in the way that might tend to obstruct the proper blood circulation of the user's hand whilst it will also be noted that no extra effort will be necessary on the part of the operator to effect a proper vibratory massage.

Whilst I have shown and described the best form of the invention at present known to me it will be obvious that the same is susceptible of minor detail changes and variations, and it is hereby intended to include all such reasonable modifications or other forms thereof as fairly fall within the scope of the appended claims.

Having described my invention, what I claim as new and desire to secure by Letters Patent is:

1. In a hand vibrator comprising a cylindrical body, a block having a hollowed out base for supporting said cylindrical body, said base comprising a front and rear supporting member and being adapted to receive the knuckles of the operator's hand therebetween, the front supporting member extending below the rear supporting member, a fibre sheet intermediate of the supporting members, a metallic plate clamped over said fibre sheet, said metallic plate being attached to the above mentioned block, resilient pads attached to said fibre sheet and bands for adjustably mounting said hand vibrator on the hand.

2. A hand vibrator comprising a cylindric body, a block having a hollowed out base including front and rear sections, a longitudinally depending tongue engaging a groove formed in said block, means for holding said body securely in place upon said block to prevent the lateral movement thereof, a fiber sheet located in the base and a metal strip supporting said sheet, insulating blocks connected to said fiber sheet and disposed beneath the rest sections and designed to be seated upon the back of the operator's hand, an adjustable leather strap provided with spaced eyelets for holding the device upon the hand, a rotatable weight located in the cylindric body and a shaft journaled in a bearing at the forward end thereof, said shaft being driven by a source of electrical energy, and an elastic band secured to the forward rest section and holding the same snugly on the fingers.

In testimony whereof I affix my signature.

EDWARD E. ZIEGLER.
